UNITED STATES PATENT OFFICE.

ANDREW J. BROOKINS, OF CHICAGO, ILLINOIS.

AUTOMATIC TRAIN-CONTROL APPARATUS.

1,339,918.

Specification of Letters Patent.

Patented May 11, 1920.

Application filed February 17, 1919. Serial No. 277,576.

To all whom it may concern:

Be it known that I, ANDREW J. BROOKINS, a citizen of the United States, and a resident of Chicago, in the county of Cook and 5 State of Illinois, have invented certain new and useful Improvements in Automatic Train-Control Apparatus, of which the following is a specification when taken in connection with the drawings accompanying 10 and forming a part hereof.

This invention relates to an apparatus operable by and in connection with a ramp rail comprising sections which are electrically controlled by track side installations of 15 an electric block railroad system.

Among the objects of the invention are to obtain an apparatus which is mechanically and pneumatically operated, said mechanical operation being effected by a ramp rail 20 which is in spaced relation to the rails of the track of the road, said ramp rail being provided with ascending and descending faces; and said pneumatic operation being effected by the air under pressure which is 25 held in storage for use in the air brake system of a train; and to obtain an apparatus which is electrically operable, said electric operation controlled by the electrical condition of the several sections which are 30 on the descending side of said ramp, (in whichever direction a train is moving on said track), said sections being insulated and electrically controlled by track and track side installations. Additional objects 35 are set forth in the description and claims.

The track side installations referred to are sufficiently identified in the drawings and described in this specification to make the operation of the apparatus understood, 40 but aside from said ramp form no part of this invention.

Additional objects sought are to obtain an apparatus which, in case a danger signal is displayed thereby, will necessitate the dis- 45 mounting of the person in charge thereof from the engine, cab or truck on which the apparatus is installed, and the manual operation of an element of the apparatus, to permit continuation of the travel of said engine, 50 cab or truck.

In the drawings Figure 1 is a side elevation of the apparatus, a ramp, a rail of the track, and a shoe, in normal position on a truck.

Fig. 2 is an elevation, at an angle of ninety 55 degrees from the view in Fig. 1, of an apparatus embodying the invention.

Fig. 3 is a vertical sectional view of the apparatus, with the shoe element thereof in its normal position. 60

Fig. 4 is a vertical section of the elements which are illustrated in Fig. 3, with the plunger up, as at the apex of a ramp, in passing thereover.

Fig. 5, is a horizontal section, on line 5—5 65 of Fig. 3, viewed in the direction indicated by the arrows.

Fig. 6, is a side elevation of a manually operable member, in an operated position.

Fig. 7 represents a lateral section of a 70 ramp, with a shoe thereon.

Fig. 8 is a diagram of a track and track side electric installation; and

Fig. 9 a diagram of one unit of the installation illustrated in Fig. 8, with the wheels 75 and axle of a truck on the track.

Reference characters applied to designate given parts indicate said parts throughout the several figures of the drawings wherever the same appear. 80

A, A' represent the case or shell of the apparatus. a represents a cylindrical wall by means of which the combined chamber and guide a' is obtained. a'' represents the inlet to chamber a'; and a''' the outlet therefrom. The parts A, A' of the shell are joined by the bolts A'', which extend through flanges A''' of said parts. B represents a shoe which is vertically movable, 85

being attached to the part A of the shell by 90 arms or levers C, C and pivots D, D'. C' represents slots through which the pivots D, D' extend. E, E, represent longitudinally movable pins in shoe B. Said pins E, 95 E, are yieldingly held in an advanced position by springs e, e, so that the ends thereof project a short distance beyond the face of the shoe, and said projecting ends are provided with the recesses E', (see Figs. 3 and 4). e' represents a plate which is an element of shoe B. F represents a plunger which is vertically movable in guide a'. The downward movement of plunger F is limited by its lower end resting on plate e' of shoe B; and its upward movement is deter- 100

mined by the movement of shoe B in sliding along on the ascending face of a ramp, as said shoe passes thereover. The normal po- 105

- sition of said plunger is determined by mechanism about to be described, said mechanism being controlled by truck and track side installations which are hereinafter set forth. Plunger F is provided with an upwardly extending well from the lower end thereof; and with the annular shoulder f' positioned some distance below the upper end thereof. F', F' represent sealing rings 10 on plunger F. Well f forms a guide for member G, which is movably mounted therein. The shoulder f' forms a movable wall of the combined chamber and guide a'. g represent sealing rings on member G. g' indicates a bore in plunger F, and g'' an annular groove on member G. The bore g' forms a passage way from the chamber a' to the groove g'', when said groove registers with the outlet of said bore. g''' is a passage way from chamber or well f (in the lower end of plunger F) through the portion of plunger F which forms the cylindrical wall of said well, and is positioned in said wall so as to register with passage way a''' when the plunger is in its extreme upward limit of travel, (the shoe B being at the apex of a ramp), and to register with annular groove g'' (member G being, at its lower end, flush with the lower end of plunger F); and said annular groove registers, at said time, with bore g'. H represents a spring and h a pin against which the lower end of spring H abuts with its upper end abutting against the bottom (upper end) of well f, tending to force the member G out of said well. I see Fig. 1 represents a pipe or conduit from outlet passage way a''' to audible signal X'.
- I' represents a head which is attached to the upper end of plunger F, as by pin I'', and said head is attached to sector J, as by pin and roller J' in slot i. The sector J is pivotally mounted on shaft j' which extends through hub j, and into part A' of the shell.
- J' represents an arm which is illustrated as integral with the sector J. K, K', represent engageable faces of projections on the peripheral face of sector J, and L a horizontally movable lever which, under conditions hereinafter set forth, is moved into the path of movement of faces K, K'. K'' represents an engageable face of a projection on the end of arm J'. L' represents a vertically movable and manually operable latch, 55 which is provided at its lower end with the abutment l', adapted to engage with the projecting face K'' of said arm J', the plunger F being at its lowest position and sector J with arm J' in corresponding position, (see Figs. 3 and 6).
- Member L see Fig. 5 is pivotally mounted on vertical member l, and the movement of said lever so that the end thereof adjacent to sector J is in or out of the path of 65 movement of the faces, K, K', is controlled by the electromagnet M and its armature m, connecting link m' and spring m''. Electromagnet M being energized the armature m is attracted thereby and moved thereto, (or nearly so), and lever L is moved into the path of movement of the faces K, K', substantially as indicated by broken lines in Fig. 5. The energizing of said magnet is in timed relation to said faces K, K', to engage with a pre-determined one thereof, by means hereinafter described.
- Plunger F being in its lowest limit of travel and sector J being in the position illustrated in Fig. 3, by the depression of member L' to the position in which it is illustrated in Fig. 6, the projection l' at the lower end thereof is forced into engagement with the face K'' on arm J', and said member is maintained in said depressed position by said engagement until said arm is moved therefrom by the movement of the plunger F as shoe B passes over the next ramp.
- In the cab of an engine or other movable body on the truck of which the hereinbefore described apparatus is mounted, there are installed electric circuits, comprising energizable signals, means to energize said signals, and conductors. Said conductors extend to terminals forming elements in this apparatus, and movable conductors or bridges which are adapted to selectively close said circuits also form elements of this apparatus; and said conductors, terminals and bridges are illustrated in Figs. 3 and 4 of the drawings, to which reference is made. In these figures the positive conductors and terminals are designated by capital reference letters and primes, and negative ones by lower case letters and primes.
- N, n; N', n'; N'', n'' are terminals, which are, respectively, arranged in pairs; and n''', n'''' are additional terminals.
- O, O', represent movable members pivotally mounted on pins O'', respectively. Members O, O' are respectively provided with the rollers O''', which are in the path of movement of the end of arm J' when said arm, sector J, and plunger F are actuated by shoe B as it moves over the ascending and descending faces of a ramp. Members O, O', respectively, are illustrated as bridges which electrically connect terminals N, n, and N' n', and also N' and n''''. The terminals N, n''' are disconnected by bridge O at the time said bridge connects terminals N, n. Terminals N'', n'' are connected by projecting member L' on vertically movable member L', when said member L' is manually depressed, as hereinbefore described.
- P represents a conductor which is in electric contact with terminal N; p a conductor in contact with terminal n; P' a conductor which branches from conductor P and is in

contact with terminal N' ; p' a conductor in contact with terminal n' ; P'' a conductor in contact with terminals N'' and n''' ; p'' a conductor attached to terminal n'' ; p''' a conductor which branches from conductor p'' and is electrically connected to terminal n'''' ; and p'''' a conductor which is electrically connected to said terminal n'''' .

S , S' , (Figs. 1 and 5) represent electric conductors which are electrically connected to the coils of magnet M , and are grounded on the frame or shell of the apparatus and the frame of the truck, respectively.

The hereinbefore described apparatus is actuated mechanically and energized electrically by a ramp rail which is secured in spaced relation to the rails of the track, and forms an element of a track side installation hereinafter described. Q , (Figs. 1, and 8), represents said ramp rail; R , R , (Figs. 1, 8 and 9), rails of a track; X' , X' , wheels on track R ; and X''' , (Fig. 9) the axle of wheels X' .

Assuming a train to be moving in the direction indicated by arrow R' , q , q' represent ascending faces of ramp Q , and r , r' descending faces thereof. Q' represents insulation. The several sections of the ramp Q are insulated from each other and from the ground or support of the ramp; and the rails R , R , of a block are insulated from the rails of an adjacent block by like insulation Q' .

It is well known to those familiar with the art of block signals for railroad operation that a track circuit which is provided with energizing means controls the position of a movable conductor in a track-side installation; and that when a train is on a track the track circuit of said block is short circuited, the coils of the electromagnet being shunted thereby, in which case there is not sufficient energy in said magnet to hold the armature thereof in position to maintain the free end of said movable conductor in electrical contact with its terminal. In reducing this invention to concrete form ramp rails form elements in the trackside installation, and Figs. 8 and 9 show, in diagrammatic form, track and trackside installations sufficient to enable the operation of the apparatus understood.

Referring to Figs. 8 and 9 the track circuits comprise, respectively, a generator W , rails R , R , of the track, conductors T , T , and the coils of electromagnet U ; and the trackside circuits comprise, in the track side installations thereof, a generator, W' , conductors T' , T' , t , t' , movable conductors u , u' , terminals V , V' and sections r , r' of the ramp.

To permit trains in both directions to be operated under this apparatus both the ascending and descending sections of the several ramps are electrically controlled by the

trackside installation; but with a train moving in a given direction on the track it is immaterial whether the ascending sections are energized or not, as said ascending sections are for the purpose of mechanically operating the shoe B and plunger F . If plunger F is in its lowest position, as shoe B moves over a ramp, said plunger is forced up by the shoe to the "attention" position, and the sector J must turn in a direction contrary to the movement of clock hands; and if said ascending sections of the ramp are energized, and lever L thereby moved into the path of movement of projecting faces K , K' , on said sector, it will be forced out of said path by the inclined faces k , k' , (Figs. 3 and 4).

The function of said ascending sections being, as stated, to raise the shoe B as said shoe slides thereover; said shoe raising said plunger F and turning sector J toward the left; the raising of said plunger at the least, will be from "clear" to "attention" position; and at the most, from "danger" to "attention" position; the movement of the plunger and sector being determined by their position prior to the shoe coming in contact with a ramp.

Before reciting the operation of the apparatus attention is directed to the pneumatic control obtained by the communication which exists between chamber a' and equalizing reservoir Y , (by conduit y and inlet a''). There is, at all times when the shoulder f' is above outlet passage way a''' , the same pressure in said chamber a' as in said reservoir, and said pressure on the shoulder f' performs several functions. In case said plunger F is in its lowest position and resting on plate e' of the shoe, as the shoe moves over a ramp said pressure holds the plunger to said plate, both in ascending and descending the ramp. In case the downward movement of the plunger is arrested by lever L being moved into the path of movement of the projecting faces K , K' of sector J , said engaged face is held closely to said lever to prevent its being jarred therefrom by the travel of the truck on the track. And when the shoe passes over the apex of a ramp, plunger F being in the position in which it is illustrated in Fig. 4, this chamber a' becomes a part or element in a passage way from equalizing reservoir Y to signal X' , and the mass or quantity of air in said chamber breaks up the continuity of said passage way, thereby obtaining a quicker response in the sounding of said signal. The chamber a' is also an element in said passage way when the plunger F is in the position in which it is illustrated in Fig. 3, that is, "danger" position,

and the rapid reduction of pressure therein producing a corresponding reduction of pressure in the equalizing reservoir hastens the sounding of signal X' .

the application of the brakes over the application which would be obtained if said chamber were not so interposed.

The operation of the apparatus is:—

- 5 Shoe B not being on a ramp is in the position in which it is illustrated in Fig. 3; this being its normal position. In going over a ramp the shoe is raised from its normal position to the position in which it is 10 illustrated in Fig. 4, forcing plunger F into the position there illustrated. The normal condition of a track over or on which a train is traveling is "clear" and hence, the normal position of sector J and plunger F existing, "clear" is indicated on a signal controlled thereby; and assuming said signal to be on the circuit of which conductors P, p, are elements, the normal position of the sector is with lever L engaged by projecting 15 face K, as is indicated by broken lines in Fig. 5, plunger F being thereby suspended, so that when the shoe passes from a ramp to assume its normal position, said plunger does not descend therewith; but spring H 20 forces member G outwardly from the well in which it is contained, and said member descends with said shoe.

- The plunger F is retained in the normal condition, (or position) above set forth, 30 when the trackside installation and the track circuit are in the conditions which are illustrated in Fig. 8, with a train in block 1 going in the direction of block 3. Under said conditions as the shoe goes over the 35 ascending sections of ramp Q, of block 1, the shoe is raised, the plunger F is raised at least from "clear" to "attention" position, an attention signal is given, and as the shoe descends on the descending sections of 40 said ramp the section r being energized by a trackside installation which comprises generator W', conductor T', movable conductor u' and again conductor T', all of block 2, conductor t from said conductor T' 45 to movable conductor u of block 3, terminal V and conductor t from said terminal V to said section r of ramp Q in block 1, the trackside circuit is completed by the elements of the cab installation which comprises shoe B, shell A, conductor S, coils 50 of electromagnet M, conductor S', the frame of truck X, wheel X', a rail R, and conductor T', back to battery W'. Electromagnet M being energized by the completion of the 55 foregoing traced circuit the armature of said magnet, (m), is attracted thereby and moves lever L into the path of projecting face K, in timed relation to the position of said projection, to engage or be engaged by said 60 projecting face.

In the carrying out the foregoing operation the plunger F is forced down with the descent of shoe B, by the pneumatic pressure in chamber a' acting on shoulder 65 f', and upon lever L being engaged with pro-

jecting face K, said pneumatic pressure firmly maintains said engagement; and the indication obtained is unchanged until said shoe passes over the next ramp.

The "clear" signal is an element of the 70 electric circuit of which the conductors P, p, terminals N, n, and bridge O are elements; but forms no part of this invention, which so far as said "clear" signal indication is concerned relates to the movement of said 75 bridge to come in contact with said terminals, and the release of terminal N from engagement with the terminal n".

Bridge O is moved by the end of arm J' to substantially the position which is indicated in Fig. 3, by broken lines, as sector J is moved to and fro by the movement of plunger F; but said sector and plunger being in normal position, (with "clear" indicated) in the up movement of the plunger 85 the "clear" circuit is simply broken, and on the down movement of said plunger, conditions being as last assumed, is remade, the section r of the ramp being energized.

In case this apparatus, being on block 1, 90 indicates, as last above set forth, a "clear" signal, the train (on the motor or engine of which the apparatus is installed), proceeds toward block 2.

If, however, at the time said apparatus is 95 on block 1, a train, cab, or car, be on block 3, as is indicated by wheels X', X', and axle X'', in Fig. 9, the electromagnet U of the track circuit of said block 3 is shunted; said track circuit being closed and comprising 100 electric generator W, rails R, R, wheels X', X', and axle X''. The electromagnet U will cease to hold the movable conductor u in contact with terminal V and section r of the ramp in block 1 will not be energized by 105 generator W' of block 2; the trackside circuit to said section r being broken at said movable conductor u in block 3. The lever L will not be moved into position, in timed 110 relation thereto, to engage or to be engaged by projecting face K, and the plunger will continue to descend with the shoe, (being forced down by pneumatic pressure in chamber a' acting on shoulder f') until said shoe is on section r'. 115

When the shoe is on said section r', with wheels X', X' on rail R, (as in Fig. 1), a track side circuit which comprises said wheels, section r' of ramp Q, the frame of the truck, conductors S, S' and the coils of 120 electromagnet M, and the trackside installations consisting of energizing means W' of block 1, conductor T', movable conductor u', terminal V', conductor T' (again), conductor t' will be closed and energized; and lever 125 L will be moved to be in engageable position, and in timed relation, with projecting face K'. Caution signal will be displayed by reason of the arm J', when lever L is engaged with projecting face K', said arm, 130

at said time, forcing the bridge O' into contact with the terminals n'''' , and n' , forcing said terminal n'''' into electrical contact with terminal N', to close the circuit of which conductors P' p' are elements; said 5 caution signal, however, forming no part of this invention; but interposed on said circuit.

In the descent of the plunger F to the 10 position where lever L is in engagement with projecting face K', the shoulder f' on said plunger is brought to substantially the position indicated by the broken line f'', Fig. 3, and a restricted discharge of air flows from 15 the chamber a', through passage way a'''.

"Caution" signal will be displayed, under the above recited conditions until the shoe comes in contact with the next ramp; and a governor circuit is continuously 20 bridged in this apparatus, comprising conductor P to conductor P', terminals N', n'''' , and conductors p''', and p''.

In case a train on block 1 receiving as last 25 above recited, a caution signal, should proceed thereunder to block 2, it would there receive the "danger" signal. The condition would be, movable conductors u, u' of block 30 3 not being in electrical contact with the terminals V, V' of said block, the trackside circuits of block 2, comprising said terminals, conductors T' and t, to block 4, and 35 return from said block to section r of the ramp rail of block 2, is broken and section r of said ramp is not energized; and the circuit comprising said conductor T', and t' to 40 section r' of said ramp is also broken, and section r' is not energized and hence, the lever L is not moved to engageable position with any of the projecting faces on sector J, 45 and the plunger descends with the descent of the shoe B, none of the terminals of the N, n, series is permanently bridged, and neither "clear" or "caution" signal circuit is closed. In addition, on the descent of the 50 plunger to the position illustrated in Fig. 3, the audible signal X'' is continuously sounded, and brakes are applied, as hereinbefore disclosed.

To release the brakes and permit the train 55 to proceed, under conditions which form no part of this invention, the member L' is depressed, and terminals N'', n'' forced into electrical contact by projection L'', to close a circuit comprising conductor P, terminals N, n'''' , conductor P'', said terminals N'', n'', and conductor p''. Said depressed position of said member L' is continuously maintained by the engagement of ends l' of member L' and K'' of arm J', until the next 60 section of track, and ramp thereto, is reached, at which time the sector J and arm J' are turned by plunger F and said member L' released. The release of said member L' causes said terminals N'', n'' to separate, 65 (by their resiliency). If danger conditions

exist on the said next section and ramp the member L' must again be depressed to re-establish the last named bridging of the governor circuit comprising said recited elements.

As recited relative to the "clear" signal, the elements of the "caution" and "danger" circuits which are contained in this apparatus, and which control the making and breaking of said circuits, are at all times 70 broken by the shoe ascending the ascending sections of a ramp, and a new indication made, although said new indication may be, and as a rule is, the same as the preceding one.

Member G at all times rests against the shoe, regardless of the position of the plunger F, being forced thereonto by spring H, and in case said shoe is not in operative position and condition, either from the 85 breaking of arms C, or one thereof, or for other reasons; said member is moved outwardly in the well f in plunger F, and a passageway for the exhaust of air from equalizing reservoir Y is automatically 90 opened, comprising the conduit y, inlet a'', chamber a', bore g', well f, and the central passage g''' in said member G. Nut h', (Fig. 3) prevents said member G from being forced entirely out of well f.

It being understood, (A), that shoe B in passing over the ascending sections of a ramp destroys the previously existing positions of the plunger F, sector J and lever L, (B), that the track installations comprising 100 rails R of a block of track, the coils of electromagnet U, the conductors T, T, connecting said coil and rails, and means W, to energize said circuit, must be in operative condition and the track of the block unoccupied to maintain movable conductors u, u', of the track side installation in contact with terminals V, V', respectively, to form continuous conductors therethrough, and (C), that the trackside installations comprising 110 said conductors, the insulated descending sections of ramps controlled thereby, and means to energize said trackside installations on the completion of the circuit comprising also the coils of electromagnet M, 115 conductors to said coils from shoe B and from said coils to a rail R of the track, upon the contact of said shoe with the descending sections of said ramps, must be in operative condition, to energize the coils of said electromagnet and actuate lever L in timed relation to sector J to arrest said sector on its return movement;—it is obvious that unless all the above recited conditions exist as said shoe moves along said descending sections of said ramps said sector will not be arrested, said plunger will not be suspended, and said plunger will be forced by pneumatic pressure on shoulder f' in chamber or space a' to follow said shoe in its descent to 120 125 130

6 "caution" or "danger" position, as the case may be.

Hence the position of sector J and plunger F, after the shoe leaves a ramp 5 may be relied on as being a representation of the conditions actually existing on the block upon which the train is entering, and upon the next block in advance. The position of said sector and plunger controls the movement 10 of the train in the following manner; if the sector and plunger are in position representing a "clear" condition of the track no brakes are applied to the train; if in position representing "caution" condition 15 the restricted passage way through passage way a''' being partially opened, as hereinbefore described, sufficient flow of air obtains to sound audible signal X''' clearly, and to make a partial application of brakes 20 and if in position representing "danger" the flow of air through said passage way a''' is so great as to sound said audible signal shrilly and to make a full application of the brakes.

25 The control of the train by the apparatus is, in the foregoing recited manner, independent of the indications which are obtained by the arm J' and the several terminals illustrated and described; and independent 30 of the operativeness of the circuits controlled thereby.

Attention is directed to the fact that the pneumatic pressure in space or chamber a' holds plunger F closely to shoe B, and holds 35 said shoe firmly to ramp Q, when said shoe, being on the descending sections of the ramp, is on a section which is thereby closed and energized by the track side battery of the track installation of which said section is an 40 element; and at said time good electrical contact of said ramp and said shoe is thereby obtained.

I claim:

1. A car carried rotatably mounted member 45 provided with engageable projections, a longitudinally movable member, means to connect said members, and a laterally movable member, in combination with track-side means to actuate said members in timed 50 relation to selectively engage said laterally movable member with said projections.

2. A rotatably mounted member provided with engageable projections, bridge members and a laterally movable member respectively engageable with said projections, in combination with means to move said 55 rotatably mounted and said laterally movable members in timed relation to selectively engage the projections adjacent thereto with said laterally movable member, and to selectively engage said bridge members with the projection adjacent thereto.

3. A rotatably mounted member movable from an initial position and returnable, and 60 means to move said member, in combination

with a plurality of electric terminals, means to connect terminals constituting a pair, said rotatably mounted member arranged, on its return movement to successively move said means to connect, and means to selectively 70 arrest the return movement of said rotatably mounted member in timed relation to the movement of said means to connect.

4. In a train control apparatus, a track-side member provided with an ascending 75 surface, in combination with a car carried mechanism, comprising a longitudinally movable member, an electroresponsive member and a member to co-act with said movable member and also with said ascending 80 surfaces of the trackside member, to mechanically move said electroresponsive member into an inoperative position on the engagement of said co-acting member and said trackside member. 85

5. In automatic train control apparatus, a trackside member provided with an ascending inclined face, in combination with a car carried device comprising a shell, a shoe movably attached to said shell and positioned 90 to ride into engagement with the ascending face of said trackside member, a member and an electroresponsive member movably mounted in said shell and adapted to co-act and lock the member against its return 95 movement, an additional member joined to said lockable member and adapted to move it forward and disengage said electroresponsive member therefrom, and means comprising a chamber in communication with 100 the air supply of the air brakes of a train to yieldingly force said additional member to an advanced position and into contact with said shoe.

6. In an automatic train control apparatus, a trackside member provided with ascending inclined faces, in combination with a car carried member adapted to ride into contact with an ascending face of said trackside member, a car carried movable member, 110 means to obtain air pressure and an audible signal arranged to be sounded by air under pressure, means to direct said air to said signal, said movable member arranged to obstruct said means, and said trackside 115 member and the car carried member arranged to contact therewith arranged to coact to remove said movable member from its obstructing position.

7. In automatic train control apparatus, a 120 trackside member, in combination with car carried members comprising, a member arranged to co-act with said trackside member, a longitudinally movable member, means consisting of air under pressure, to yieldingly hold said movable member in contact with said co-acting member, an additional member movably mounted on said longitudinally movable member, means to hold said additional member in contact 125 130

with said co-acting member, and a passage way for the flow of air under pressure therethrough, said additional member arranged to obstruct said passage way, and said co-acting member arranged to hold said additional member in position obstructing said passage way.

8. In automatic train control apparatus, car carried mechanism comprising a movable member, means to apply air under pressure to said member, an additional movable member and means to connect said members, in combination with an electroresponsive member engageable with said additional member, said air under pressure arranged to yieldingly hold said movable member in position to force said additional member to said electroresponsive member, when engaged therewith, to retain said engagement.

10 9. In automatic train control apparatus, car carried mechanism comprising a longitudinally movable member, a sector provided with projections, means to connect said member and said sector, an electroresponsive member, and means to selectively engage said electroresponsive member and said projections, said members arranged to co-act so that movement of said longitudinally movable member in one direction releases said selective engagement, and said engagement prevents the movement of said sector and longitudinally movable member in the return direction, all combined as set forth.

35 10. In car carried mechanism of automatic train control apparatus, a longitudinally movable member, a sector, means to connect said member and said sector, projections on said sector in spaced relation to said member, an audible signal, and means, comprising the equalizing reservoir of a train air brake system and a communicating passage way, to supply air under pressure to said signal, said member arranged to obstruct said passage way when in normal position and to be movable from said normal position to partially obstruct said passage way, in combination with an electroresponsive member, and means to selectively engage said responsive member and said projections, to maintain said first named member in said normal and in said partially obstructing position.

11. In car carried mechanism of automatic train control apparatus, a longitudinally movable member, a sector, means to connect said member and said sector, projections on said sector in spaced relation to said member, an audible signal, and means, comprising the equalizing reservoir of a train air brake system and a communicating passage way, to supply air under pressure to said signal, said member arranged to obstruct said passage way when in normal position and to be movable in a plurality of

directions from said normal position to partially obstruct said passage way, in combination with an electroresponsive member and means comprising track and trackside installations, to selectively engage said responsive member and said projections to maintain said movable member in said normal and in said partially obstructing position by arresting the movement thereof in the return one of said directions.

12. In car carried mechanism of automatic train control apparatus, a longitudinally movable member, an additional member, an audible signal, and means comprising a train air brake system and a communicating passage way to apply air under pressure to said first named member and to supply said air to said signal, in combination with means comprising a trackside installation to move said first named member a determined limit of travel and to permit the return movement thereof by said air pressure in continuous contact with said additional member, said first named member arranged to obstruct said passage way at determined intervals of the travel thereof.

13. In car carried mechanism of automatic train control apparatus, electric terminals, bridge members, a pivotally movable member, a longitudinally movable member and a connection between said members to selectively connect said terminals, in combination with trackside means to move said longitudinally movable member in one direction, and car carried means to apply pneumatic pressure thereto to yieldingly move it in the return direction, said pivotally movable member arranged to co-act with said bridge members, and means in timed relation with said co-acting means to arrest the return movement of said pivotally and longitudinally movable members.

14. In car carried mechanism of car control apparatus, a movable member, means to limit the forward and return travel of said member, electric terminals and additional electric terminals, a plurality of controlling means to selectively connect and disconnect said terminals and manually operable means to connect said additional terminals, a projecting element on said movable member to successively operate said plurality of means, said plurality of means, said projecting element and said manually operable means in spaced relation, and, said movable member being at the limit of its return travel, said projecting element and said manually operable means engageable to retain said means in an operated position.

15. In car carried mechanism of car control apparatus, a movable member, electric terminals and additional electric terminals, a plurality of controlling means to selectively connect and disconnect said terminals, and manually operable means to con-

nect said additional terminals, a projecting element on said movable member to successively operate said plurality of means, said plurality of means, said projecting element and said manually operable means in spaced relation, and additional car carried members, in combination with a trackside member, said additional car carried members and said trackside member arranged to 10 co-act to move said movable member to a forward limit of travel, and to permit the return thereof to a return limit of travel, and said movable member being at the limit of its return travel said projecting element 15 and said manually operable means engageable to retain said operable means in an operated position, until forward movement of said movable member.

16. A trackside installation comprising a source of electrical energy, a member consisting of insulated sections having ascending and descending faces, and means to selectively conduct electrical energy from said source to said sections, in combination with a car carried member adapted to co-act with said faces, a movable plunger arranged to be moved by said co-acting car carried member and returnable to its initial position, an electroresponsive member operable to arrest said return of said plunger, and conductors from said co-acting member to said electroresponsive member and to a rail of a track, said sections provided with said depending faces, said plunger, and said electroresponsive member in timed relation to control the movement of said member and plunger to selectively arrest said return movement of said plunger.

17. A trackside installation comprising
40 a source of electrical energy, a member con-
sisting of insulated sections having ascending
and descending faces, and means to
selectively conduct electrical energy from
said source to said sections, in combination
45 with a car carried member adapted and
positioned to co-act mechanically with said
trackside member, a plunger arranged to
be moved by said co-acting member and re-
turnable on the return movement of said
50 co-acting member, an additional member,
projections on said additional member, and
a connection between said additional mem-
ber and said plunger, an electroresponsive
member operably movable into the path of
55 movement of said projections, said projec-
tions adapted to move said responsive mem-
ber out of said path on said plunger and ad-
ditional member being advanced by the en-
gagement of said co-acting member and said
60 trackside member and to lock therewith on
the return movement of said plunger and
additional member, and conductors from
said co-acting member to said electrore-
sponsive member and from said member to
65 a rail of a track, whereby a timed relation

between said projections and said responsive member is obtained.

18. A trackside installation comprising a source of electric energy, a member consisting of insulated sections provided with ascending and descending faces, and means to selectively conduct said energy from said source to said sections having descending faces, in combination with car carried mechanism comprising a member adapted and positioned to be moved into engagement with said trackside member, to co-act mechanically with the sections having ascending faces and electrically with the sections having descending faces, a plunger, means to apply pneumatic pressure to said plunger, an additional member, projections on said additional member and a connection between said additional member and said plunger, said co-acting member arranged to move said plunger and advance said additional member, and said pressure arranged to hold said plunger to contact with said co-acting member to force the meeting faces of said co-acting member against the ascending and descending faces of said trackside member, an electroresponsive member operably movable into the path of said projections, said projections adapted to move said responsive member out of said path on the advance movement of said additional member and to lock therewith on the return movement thereof, to arrest said return movement, and conductors from said co-acting member to said electroresponsive member and from said member to a rail of a track.

19. A trackside installation comprising a source of electric energy, a member consisting of insulated sections provided with ascending and descending faces, and means to selectively conduct said energy from said source to said sections having descending faces, in combination with car carried mechanism comprising a member adapted and positioned to be moved into engagement with said trackside member, to co-act mechanically with the sections having ascending faces and electrically with the sections having descending faces, a plunger, means to apply pneumatic pressure to said plunger, an additional member, projections on said additional member and a connection between said additional member and said plunger, said co-acting member arranged to move said plunger and advance said additional member, and said pressure arranged to hold said plunger to contact with said co-acting member to force said co-acting member against the ascending and descending faces of said trackside member, electrical terminals, a plurality of controlling means to selectively connect and disconnect said terminals, an additional projection on said additional movable member to successively operate said plurality of means, an electroresponsive 130

member operably movable into the path of movement of said first named projections, said first named projections being adapted to move said responsive member out of said path on the advance movement of said additional member and to lock therewith on the return movement thereof to arrest said return movement and selectively maintain said

plurality of means in an operated position, and conductors connecting said responsive 10 member to said co-acting member and to a rail of a track.
